(57) **CLAIM**

The ornamental design for a sports climbing shoe, as shown and described.

DESCRIPTION

FIG. 1 is a perspective view of a design relating to the sports climbing shoe;

FIG. 2 is a right side view thereof;

FIG. 3 is a front view thereof;

FIG. 4 is a rear view thereof; and,

FIG. 5 is a top view thereof.

Portions of the bottom and left side of the shoe that are not shown in the figures form no part of the claim design.
